Jerome H. Steinberg, Brooklyn, N. Y.

Application February 1, 1946, Serial No. 126,165

Term of patent 3½ years

(Cl. D48—20)

To all whom it may concern:

Be it known that I, Jerome H. Steinberg, a citizen of the United States, residing at Brooklyn, in the county of Kings and State of New York, have invented a new, original, and ornamental Design for a Combined Desk Set and Lamp Standard, of which the following is a specification, reference being had to the accompanying drawing, forming part thereof.

In the drawing:

Fig. 1 is a front view of a combined desk set and lamp standard showing my new design;

Fig. 2 is a top view, and

Fig. 3 is a side view thereof.

I claim:

The ornamental design for a combined desk set and lamp standard, substantially as shown.
JEROME H. STEINBERG.
